UNITED STATES PATENT OFFICE.

LOUIS A. JANSSEN, OF PITTSBURGH, PENNSYLVANIA.

VALVE-PLUG REMOVER.

Application filed October 26, 1922. Serial No. 597,148.

To all whom it may concern:

Be it known that I, LOUIS A. JANSSEN, a citizen of the United States of America, residing at Pittsburgh, in the county of Allegheny and State of Pennsylvania, have invented certain new and useful Improvements in Valve-Plug Removers, of which the following is a specification.

This invention relates to a valve plug remover, adapted particularly for the insertion and removal of valve plugs in automobile engines, which plugs are employed to close the ports in the engine head, through which the valves are accessible.

These valve plugs are threaded in the port openings and are themselves threaded to receive the spark plug or priming cup, the valve plugs receiving the spark plugs being arranged above the inlet valves and the valve plugs receiving priming cups being arranged above the exhaust valves. Outside of the independent construction of these valve plugs for the reception of the spark plugs and priming cups, the valve plugs are identical and are designed to be threaded into the engine head to maintain a sealing connection therewith. It is necessary to remove these valve plugs to gain access to the valves, and this is ordinarily an infrequent operation, the valve plugs will become so tightly seated through continued reheating and trust that their removal is a matter of extreme difficulty. Furthermore, in the application of these valve plugs, it is highly desirable that they be seated to avoid all possibility of leakage and this requires the application of some considerable power in finally drawing the plugs down to a sealing position.

Various tools have been suggested for the removal of these valve plugs, and these tools have, as a rule, proven unsatisfactory for the reason that they are liable under the application of the necessary power to slip out of connection with the recesses in the valve plugs. This has been recognized as such a disadvantage of the tools now on the market for this purpose, that ordinarily the mechanic in removal or finally applying the valve plugs will use a tool such as a screw driver or the like and turn the plugs by a hammer blow on the screw driver with the end of the screw driver engaged in the plug

recesses in succession. This method of applying and removing these plugs, which is 55 the one usually employed by most mechanics, soon results in marring the square edges of the plug recesses, and thus even the best type of tool heretofore offered for this purpose would therefore be of little utility 60 as the engaging portion of the tool would ride over these rounded or marred recess edges under the application of power.

It is the object therefore of the present invention to provide a tool by means of 65 which the valve plugs may be removed and applied no matter whether the edges of the recesses may or may not be marred or rounded, the improved tool being constructed for a relatively fixed relation with the 70 plug independent of the connection between the tool and recesses of the plug, there being additionally provided a member which may be conveniently applied to the tool proper after the latter has been connected 75 with the plug, this member being designed to engage in the recesses of the plug to thereby permit a turning operation of the tool to similarly turn the plug.

The invention is illustrated in the accompanying drawings, in which:

Fig. 1 is a broken perspective view, showing an engine head provided with a series of valve plugs, the improved tool being shown in cooperative relation with one of 85 said plugs;

Fig. 2 is an enlarged broken vertical sectional view partly in elevation, one end of the tool being shown in connection with a valve plug; and

Fig. 3 is a perspective view of the tool and valve plug, the parts of the tool being shown separated.

A tool of this application is designed to cooperate with port plugs 1, which plugs 95 have a reduced lower portion 2 exteriorly threaded at 3 to cooperate with threaded openings in the engine head 4. The plug is interiorly threaded at 5 with this opening of a diameter in some plugs to receive the 100 usual spark plug 6, and in other plugs to receive the usual priming cup 7. The plug is further provided with an upstanding flange 8 formed with diametrically opposed recesses 9, the interior diameter of the 105 flange being such as to provide an abrupt

shoulder 10 inwardly of the flange and beyond the threaded opening 5. The plug is circumferentially enlarged above the threaded portion 3, providing a shoulder 11 to 5 overlie the engine head, there being usually provided a circular gasket resting between this shoulder 11 and the engine head, and acting to seal the juncture between the valve plug and head when the plug is in place. 10 These plugs are applied and removed through the threaded connection 3 with the engine head, and after the plugs have been in position for some time, they become so intimately connected with the engine head 15 as to be almost impossible of removal with the ordinary tool. Furthermore, in initially applying these valve plugs, it is necessary to seat them very tightly in order to prevent leakage and this also requires the application of considerable power.

The improved tool for this purpose comprises a bar 12 of appropriate length formed at each end with a cylindrical portion 13, and beyond the cylindrical portion with a 20 reduced threaded extension. As previously stated, the valve plugs have their openings 5 of different sizes for receiving the spark plugs or priming cups, and as the present tool is designed for cooperation with the 25 valve plugs of an engine, one of such threaded projections as 14 will be of a size to cooperate with the spark plug opening of the valve plug, while the other projection as 15 will be of a size to cooperate with the 30 priming cup opening of the valve plug. These projections 14 and 15 are exteriorly threaded to cooperate with the threaded 35 openings interiorly of the valve plugs, the single tool thus providing for engagement 40 with both sets of valve plugs of the engine. The cylindrical portion 13 at each end of the main body 12 is of slightly less diameter than the interior of the flange 8 of the 45 port plug, that end of the cylindrical portions 13 or 14, from which the threaded projection extends, providing a shoulder 16, which when the tool is threadedly connected 50 with the particular valve plug bears squarely upon the shoulder 10 of such valve plug. 55 The projections 13 of the tool proper are formed with diametric openings 17, of non-circular form, such openings being shown square in cross-section. A lock-bar 18 of a 60 size to slidably fit in either of the openings 17 forms a part of the tool proper, this bar 65 being of such length that it will extend in both directions beyond the outer surface of the cylindrical portions 13 of the tool, and in such extended portions, as at 19, Fig. 2, 70 will engage in a pair of diametrically opposed recesses 9 of the valve plug. It is of course understood that the bar 18 is of a size to more or less snugly fit said recesses 9, and that as the tool is connected with the plug 75 through a threaded connection, such tool

may be turned to cause the bar 18 to cooperate with either pair of diametrically opposed notches 9 of the valve plug. A set-screw 20 is arranged for threaded cooperation with each cylindrical portion 13, this set-screw 70 being designed to engage the lock-bar 18 when the latter is in position and prevent accidental movement of the lock bar during operation of the tool. The position of the set-screw is at approximately right angles 75 to the plane of the opening 17, hence with the lock-bar engaging any pair of notches 9, the set-screw will be accessible through one of the remaining pair of notches.

In the use of the improved tool, the lock-bar 18 is removed from the tool proper and the projections 14 or 15, in accordance with the type of valve plug being removed, is threaded into the interior opening of the particular valve plug following the removal 80 of the spark plug or priming cup therefrom. The tool is screwed into place until the shoulder 16 practically engages the shoulder 10 or so that the particular opening 17 of the tool will be aligned with a pair of diametrically opposed notches 9 of the valve plug. The lock-bar 18 is then passed through these notches and openings 17 with the ends of the lock-bar resting in the opposed notches, as clearly shown in Fig. 2. 90 The set-screw 20 may then be tightened to prevent accidental movement of the lock-bar, and the tool proper will be then turned to correspondingly turn the valve plug.

To provide for convenience in operating 100 the tool, the central portion of the body is formed with a non-circular portion 21 adapted to receive a wrench, this portion 21 being also formed with an opening 22 to removably receive a rod 23 for convenience in 105 turning the tool. For ordinary purposes, the tool may be conveniently operated through the use of rod 23, though where unusual power is required for the removal of the plug, a wrench of appropriate length 110 to give desired leverage may be applied to the portion 21 for turning the tool.

It is to be particularly noted that the improved tool is positively connected with the valve plug through the threaded connection 115 therewith, and that hence so far as independent longitudinal movement is concerned, the tool proper and valve plug are inseparable. The use of the lock-bar serves merely to connect the tool and valve plug 120 against independent rotary movement, so that any rotation of the tool will correspondingly effect the valve plug. As the tool is held against independent longitudinal movement with respect to the plug, it follows that 125 the locking bar 18 will serve to turn the plug no matter what the condition of the edges of the notches 9 may be, for as long as these notches exist as such, the locking bar is bound to exert a turning influence on the 130

plug in the turning of the tool, as the tool cannot move longitudinally with respect to the plug owing to the threaded connection between the tool and plug.

5 5. Claims:

1. A valve plug tool, including a member adapted for threaded connection with the plug to secure the plug and member against relative endwise movement, and removable means to engage the member and plug to prevent relative rotary movement.

10 2. A valve plug tool, including a member having a projection adapted for threaded connection with the valve plug, and a bar

15 adapted to slidably engage the member and project beyond the same to seat in the notches in the valve plug, whereby to hold the member and plug against independent rotary movement.

20 3. A valve plug tool, including a member having a projection adapted for threaded connection with the valve plug, a bar adapted to slidably engage the member and project beyond the same to seat in the notches 25 in the valve plug, whereby to hold the member and plug against independent rotary movement, and means to secure the bar against movement relative to the member.

4. A valve plug member, comprising a body having a threaded extension at one end to engage the threaded opening in a valve plug, said body being formed above said threaded extension with a diametrically arranged opening, and a bar adapted to be 30 passed through said opening and project in 35 both directions beyond the body.

5. A valve plug member, comprising a body having a threaded extension at one end to engage the threaded opening in a valve 40 plug, said body being formed above said threaded extension with a diametrically ar-

ranged opening, a bar adapted to be passed through said opening and project in both directions beyond the body, and means for securing the bar relative to the body.

45

6. A valve plug tool, comprising a body formed at each end with a threaded projection, the projections being relatively of difference diameters, said body being formed adjacent each projection with a diametrically arranged opening of non-circular form in cross-section, and a locking bar of a length exceeding the diameter of the body and adapted to cooperate with either of said 50 55 openings.

7. A valve plug tool, comprising a body formed at each end with a threaded projection, the projections being relatively of difference diameters, said body being formed adjacent each projection with a diametrically arranged opening of non-circular form in cross section, and a locking bar of a length exceeding the diameter of the body and adapted to cooperate with either of said 60 65 openings, said body being formed intermediate its ends with a wrench engaging portion.

8. A valve plug tool, comprising a body formed at each end with a threaded projection, the projections being relatively of different diameters, said body being formed 70 adjacent each projection with a diametrically arranged opening of non-circular form in cross-section, and a locking bar of a length exceeding the diameter of the body and adapted to cooperate with either of said 75 openings, said body being formed intermediate its ends with a transverse opening to receive an operating rod for turning the body.

In testimony whereof I affix my signature.

LOUIS A. JANSSEN. [L.S.]
